UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A FRAME FOR TABLES, &c.

SPECIFICATION forming part of Design No. 23,421, dated July 3, 1894.

Application filed May 21, 1894. Serial No. 512,011. Term of patent 3½ years.

To all whom it may concern:

Be it known that I, LOTHAR VON GRAVE, a subject of the Emperor of Germany, residing at Wallingford, New Haven county, State of Connecticut, have invented and produced a new and original Design for Frames for Tables, &c., of which the following is a specification, reference being had to the accompanying drawings, wherein—

Figure 1 is a perspective view of a table embodying my design. Fig. 2 is a plan view clearly illustrating my design, one-half being shown in full lines and one-half in outline.

The essential features of my design consist of an ornamental frame of openwork leaf-like

formation having characteristics of rococo scroll with grille, shield-like ornaments extending therefrom.

In the drawings, *a* represents the ornamental frame of openwork leaf-like formation *b* having characteristics of rococo scroll with grille shield-like ornaments *c* projecting therefrom.

What I claim is—

The design for frames for tables &c., substantially as shown and described.

LOTHAR VON GRAVE.
